UNITED STATES PATENT OFFICE.

CLEMMA R. RANEY, OF CHICAGO, ILLINOIS, ASSIGNOR TO INTERNATIONAL HAR-
VESTER COMPANY, A CORPORATION OF NEW JERSEY.

SHOCKER.

Application filed July 26, 1919. Serial No. 313,588.

This invention relates to shockers, and more particularly to the type of shocker, in which the sheaves are deposited in a suitable receptacle and are dropped therefrom when a shock of sufficient size has been formed.

If the shocker is to successfully set up shocks in the field, it will be evident that shocks should be formed as symmetrical as possible. Therefore, one of the objects of this invention is to assist the forming of such shocks and thereby insure the successful operation of the shocker.

A more specific object of my invention is to provide an improved means for controlling the discharge mechanism, whereby the discharge mechanism is operated only when a symmetrical shock is formed.

The construction of the shocker herein described and illustrated comprises an oscillating sheaf delivery member which delivers sheaves to the shock receptacle and controls the tripping mechanism for throwing into operation the shock binding and discharging mechanisms when a predetermined height has been reached by the sheaves in the receptacle. The invention further comprises an improvement on this construction in which the above mentioned tripping mechanism is rendered operable only when an even number of sheaves has been deposited in the receptacle.

In the accompanying drawings I have, for the purpose of illustration, shown one embodiment of my invention which may be assumed in practice.

Fig. 1 is a top plan view of the shocker;

Fig. 2 is a side elevation of Fig. 1, with certain parts omitted for the purpose of clearness;

Fig. 3 is a fragmentary top plan view, partly in section taken on the line 3-3 in Fig. 2 showing the mechanism for controlling the size control mechanism;

Fig. 4 is a cross-sectional view of that part of a shocker mechanism taken on the line 4-4 in Fig. 1;

Fig. 5 is a cross-sectional view of the size control mechanism taken on the line 5-5 in Fig. 1 showing the connection to the tripping mechanism;

Fig. 6 is an enlarged detail sectional view taken on the line 6-6 in Fig. 4, looking in the direction of the arrows.

55 The shocker illustrated is the standard type,

and comprises a U-shaped frame 10 carrying a supplemental frame member 11, and provided with a forwardly projecting tongue 12 which is slidably supported at 13 on a laterally projecting support pipe 14 carried by 60 the binder. The shocker is also provided with the usual sheaf delivery fork 15 pivoted for lateral movement at 16 to the bracket 16'. This lateral movement is used in connection with the alternating delivery of the 65 sheaves first on one side of the receptacle and then on the other. Bracket 16' is secured to the shaft 17, which is oscillatably carried by the brackets 53 secured to the vertically supported members 51 mounted on the frame 70 10. The delivery fork 15 is oscillatable in a fore and aft direction to deliver sheaves received from the binding mechanism (not shown) to the upwardly and rearwardly 75 tilttable shocker receptacle 18 pivoted at 19 to the main frame pipe.

The mechanisms for operating the sheaf delivery member, whereby the sheaves are deposited in the shock receptacle, will first be described.

The sheaf delivery member 15 is operated from the power shaft 20 through suitable bevel gears 21, and a transversely extending and continuously running shaft 22, having fixed thereon a sprocket 23 geared to the clutch sprocket 24 by means of a chain 25. Clutch sprocket 24 is journaled on the shaft 26, and the sprocket and shaft are held out of engagement by the pawl 27 and pawl controlling member 28. The shaft 26 has fixed on the end opposite the clutch sprocket 24, a crank 29, which is connected to the shaft 17 which carries the delivery fork through the link 30 and crank arm 31. In this way the oscillatory motion is transmitted to the fork arm 15.

For a more detailed description of these mechanisms, see my Patent No. 1,242,112, October 2, 1917.

The binding and discharging mechanism 100 is operated through the shaft 22, above mentioned, which has fixed thereon a clutch disk 32, and a clutch engaging member or pawl 33 pivotally supported on one side of the bevel gear 34 which is journaled on 105 the shaft 22 and in mesh with the bevel gear 35, fixed to the forward end of the rearwardly extending shaft 36 which is journaled in the bearing brackets 37 and 38 carried by the frame 10. Intermediate the ends 110

of the shaft 36 is a sprocket 39 fixed thereto and connected by means of the chain 40 to a sprocket 41, secured to a knotter shaft 42, which in turn operates the needle 43 through the pitman connection 44. The knotter shaft 42 has fixed adjacent to the rear end thereof, a crank 45, having a link 46 pivoted thereon and operatively connected to the crank 47 mounted on the shaft 48. 10 The stubbleward end of said shaft has formed integrally therewith a forwardly extending crank arm 49, having a roller 50 engaging the bottom of the receptacle 18 for tilting said receptacle.

15 Inasmuch as no invention, per se, is claimed in this application for the specific construction above described, a more detailed description of this mechanism has not been given. For a further description of this 20 type of shocker, see Patent #1,242,112, October 2, 1917.

A tripping mechanism for controlling the actuation of the shocker, binding and discharging mechanism will next be described.

25 Reference is made to Figs. 1, 2 and 5.

This mechanism is mounted upon two oppositely disposed frame members 51, and comprises a cam member 52 carried by the bracket 53 in which the oscillating shaft 30 17 is journaled. This cam is substantially arc-shaped, and as shown, is slightly eccentric with respect to said shaft, and provided with an overturned or laterally extending flange at one side thereof, which extends 35 toward the movable sheaf delivery fork. A tripping member 54 is secured to the shaft 17 in a position intermediate cam 52 and sheaf delivery fork 15. This tripping member 54 is movable with the shaft 17 and 40 sheaf delivery fork 15. The member 54 has pivoted thereto and extending laterally therefrom a bell crank member 55 which is provided at one end with a roller 56 and at its opposite end with a lug 57 flattened upon one of its faces. The bell crank 45 member 55 is normally held in a predetermined position with respect to member 54 by means of a flat spring 58 fixed at one end of member 54, the free end of the spring 50 engaging the flat surface of the lug 57. When the delivery fork member 15 is moved with the shaft 17 upwardly and rearwardly about its pivot to sheaf discharging position, the pivoted crank member 55, also 55 carried by the shaft 17, is thrown back about its pivot to depress the flat spring 58, and the roller 56 rides over the upper surface of the cam 52. When, however, the roller 56 passes over the end of the cam 52, the 60 spring 58 is automatically relieved, so that it is free to throw the bell crank 55 about its pivot into such a position that when the arm 15 is moved to sheaf receiving position, the roller 56 rides on the under surface of 65 the cam 52. Thus, when the arm 15 is

removed back and forth in its normal operation of filling the sheaf receiving receptacle 18, the bell crank 55 moves therewith and carries the roller 56 which rides over the upper surface of the cam 52 when the arm 70 15 is moved to sheaf discharging position, and engages with the under surface of the cam, when the sheaf delivery arm 15 is returned to sheaf receiving position. Co-operating with the movable member 55 and 75 engaged with the latter in its movement along the cam 52 is a tripping member 59 pivoted at 60 to a horizontally extending stud formed upon the bracket 53, above the cam 52, in such a position that said tripping member 59 is in the path of the roller 56, as said roller is moved forwardly and rearwardly on the upper surface of the cam 52. It will be understood that the roller 56 rides on the upper surface of the cam 80 52 on its forward movement only when the sheaves have reached a predetermined height or a sufficient bulk is accumulated to form a shock in the receptacle.

The above described mechanism per se does not form a part of this invention. It is understood, however, that the mechanism shown here is adapted to operate substantially the same way as that described in my 85 Patent #1,231,195, June 26, 1917.

The sheaf delivery member 15 in its oscillating movement of delivering sheaves from the binding mechanism of the harvester to the receptacle of the shocker is alternately deflected to the opposite sides of the receptacle by means of a loop member 62 fixed to the sheaf delivery member 15 and encircling the bail or arm guiding member 63 pivotally supported on the shocker frame. The bail member 63 is oscillated by the vertically 90 disposed shaft 64 which has a slotted crank portion 65, which is adapted to pivotally support the bail member 63. The shaft 64 is journaled in the bearing 66, and has a crank 67 secured thereto adjacent its lower 95 end, which is suitably connected by means of a link 68 to a pair of two-to-one gears 69' and 69 respectively for oscillating the bail member 63. In the operation of the 100 above described mechanism the shaft 26 is 110 driven by the main shaft 22 through the sprockets 23, 24 and the chain 25. The smaller gear 69 being fixed to the shaft 26 drives the larger gear 69' which in turn oscillates the vertically disposed shaft 64 115 through the connections 68 and crank 67 fixed to the shaft 64. The oscillation of the shaft 64 swings the bail 63 in a manner to deflect the fork 16 laterally in its normal 120 operation in delivering the sheaves into the receptacle of the shocker. It will be seen that one complete rotation of the shaft 26 through the 2 to 1 gears 69' and 69 respectively 125 swings the bail 63 from the dotted line position to the full line position shown 130

in Fig. 4 and a second rotation of this shaft will swing the bail 63 from the full line position to the dotted line position in this figure. For a more detailed description of this construction, see Patent No. 1,242,112, Oct. 2, 1917 above mentioned.

The specific mechanism which forms the present invention cooperates with the above described mechanisms in such a manner that the tripping mechanism can be actuated only when an even number of sheaves is deposited in the receptacle. A detailed description of this controlling mechanism will next be given.

The tripping member 59 is connected through the link 61 with the crank 70, and a coil spring 71 is provided between the last two mentioned members to take up the movement of the tripping member 59 and rod 61. As the sheaf delivery fork member is moved rearwardly to a discharging position, carrying with it the crank 55, the spring 71 automatically returns the tripping member 59 to normal position. The crank 70 is secured to or formed integrally with a transversely extending shaft 72, which in turn is journaled at one end in the bearing 73, and at the opposite end in the bearing bracket 74, slotted as shown at 74', said bracket being fixed to the frame member 75 carried by the shocker frame. The shaft 72 is provided at the end opposite the crank 70 with a rearwardly extending crank 76, having an eye 77 formed on the free end thereof for the reception of a link 78, which is pivotally connected to a latch member 33', whereby said latch member may be swung on its pivot 79 on the bearing bracket 37. As is shown in Fig. 6, the bearing bracket 74 has formed integrally therewith a downwardly extending portion 80, to which is pivoted at 81 a lever 82, which carries intermediate its ends a roller 83 disposed in the path of the shaft 72 as said shaft is moved laterally in the slot 74' of the bearing bracket 74. Pivottally connected to the free end of the lever 82 is one end of the rod 84, the opposite end of which has fixed thereon a U-shaped member 85 adapted to engage the bail member 63, and pivotally secured thereto in a position above the crank 65 by means of a cotter pin 86. It will be seen that as the bail 63 is oscillated from one side to the other, the lever 82 is also oscillated about its pivot 81 by means of the connection 84, as shown in Figs. 3 and 4.

The operation of the construction shown is as follows:

When the sheaf delivery arm 15 is rotated about its pivot from the sheaf receiving position to a sheaf discharging position, roller 56 of the bell crank 55 moves over the upper surface of the cam 52. Roller 56 during this movement engages the tripping member 59, but does not trip the latch 33',

as the rod 61 is slidable freely on the crank 70, and spring 71 yields to permit this movement. Upon the return of the sheaf delivery arm 15 to sheaf receiving position the roller 56 rides on the under surface of the cam 52. This is the normal course roller 56 travels until a predetermined height has been reached by the sheaves deposited in the receptacle 18.

The sheaf delivery fork arm 15, in the course of filling the receptacle 18 is actuated through an arc of decreasing amplitude as the shock is being gradually built up until a predetermined height of the shock has been reached, at which time the roller 56 remains on the upper surface of the cam 52 and is returned over this surface, engaging the tripping member 59 which in turn trips the latch 33' through the connections 61, cranks 70, 76 and link 78. It will be seen that when the bail 63 is in the position shown in full lines in Figs. 3 and 4, and the roller 83 is held in a position to retain the shaft 72 in the upper portion of the slot 74' (see Fig. 6) that the movement imparted by the roller 56 to the tripping member 59 will cause the shaft 72 to oscillate in the bearing 73 and on the roller 83 by means of the link connection 61. The oscillation of the shaft 72 will raise the free end of crank 76, and thus trip the latch 33' by means of the link connection 78. The raising of the latch 33' releases the pawl 33 and sets into operation the shock binding and discharging mechanism by connecting the continuously operating clutch member (not shown) in the clutch 32 with the intermittently operating gear 34 which carries the pawl 33. The gear 34 is driven from the power shaft 20 through the gears 21 and the main shaft 22. The gear 35 which is in mesh with the gear 34, drives the shaft 36 which in turn drives an outer shaft 42 by means of sprockets 39, 41 and chain 40. Then through the pitman connection 44 connecting the shaft 42 with the needle 43, the needle is actuated to tie the twine around the shock prior to setting the same up.

It will be further seen that when the bail 63 is in the position shown in dotted lines in Figs. 3 and 4, the roller 83 which is rotatably supported on the lever 82 is swung out of supporting engagement with the shaft 72 by reason of the lever 82 being swung downwardly about its pivot 81 by the connecting rod 80 which is connected to the bail 63. When the support or bearing which the roller 83 forms for the shaft 72 is withdrawn, the movement imparted to the tripping member 59 will cause the shaft 72 through the crank 70 to swing downwardly or outwardly from its normal axis of oscillation, in the slot 74' of the bracket 74. During this downward or outward movement of the shaft 72 in the slot 74', the

free end of the crank 76 and its eye 77 remains substantially stationary. In other words, the tripping mechanism, that is, the pawl 33, connection 78, crank shaft 72, connecting rod 61 and tripping member 59, is rendered inoperative when the bail 63 is in the dotted line position shown in Figs. 3 and 4. It is quite evident, therefore, that the tripping mechanism is only operable 10 when the sheaf delivery member 15 is depositing a sheaf on one side of the receptacle after a predetermined height has been reached by the sheaves deposited in the receptacle.

15 It will be seen from the above described operation that the tripping mechanism is rendered inoperative when the sheaf delivery member is depositing a sheaf on the side of the receptacle in which the bail member 63 20 assumes the position shown in the dotted lines of Figs. 3 and 4; and it follows therefore that the shock binding and discharging mechanism can be set into operation only when an even number of sheaves has reached 25 a predetermined height in the shock receptacle 18; in other words, the binding and discharging mechanism of the shocker can only be thrown into operation when the sheaf discharging member is returning from depositing a sheaf at one particular side of the receptacle, which happens to be the knotter side of the receptacle in this particular construction, but with a slight variation 30 in the construction it may be changed to the other or needle side of the receptacle.

40 While I have described one embodiment of my invention in this application, it is of course to be understood that the embodiment shown herein is susceptible of modification without departing from the spirit of my invention.

45 What I claim as my invention and desire to secure by Letters Patent is:

1. In a shocker, a frame, a sheaf receptacle pivotally carried thereby, a binding mechanism mounted on said frame, a sheaf delivery member carried by said frame for delivering single sheaves to said receptacle and for controlling said binding mechanism, 50 and means for actuating said mechanism when an even number of sheaves has been deposited in said receptacle.

55 2. In a shocking machine, a shock receptacle, operating mechanism therefor including a trip and a single sheaf delivery member engageable with the upper surface of the shock in said receptacle, said delivery member engaging said trip, and means connected to said trip for controlling the actuation of said mechanism when said member has deposited an even number of sheaves and the sheaves have reached a predetermined height in said shock receptacle.

60 3. In a shocker, a frame, a sheaf receptacle pivotally carried thereby, a sheaf delivery

member mounted on said frame for delivering single sheaves to said receptacle, binding and discharging mechanism carried by said frame, and means including an outwardly movable shaft positioned adjacent 70 said sheaf delivery member for controlling the actuation of said binding and discharging mechanism when an even number of sheaves has been deposited in said receptacle.

4. In a shocker, a frame, a sheaf receptacle pivotally carried thereby, a sheaf delivery member pivotally mounted on said frame for depositing sheaves one at a time in said receptacle, operating mechanism for oscillating said sheaf delivery member, and supplemental means including a shaft movable outwardly with respect to its normal oscillatory axis for controlling the operation of said sheaf receptacle about its pivot when an even number of sheaves has been deposited 80 therein.

5. In a shocker, a movable sheaf delivery member for delivering single sheaves, a dumping sheaf receptacle receiving sheaves therefrom, means set in operation by said sheaf delivery member for binding and discharging in the form of a shock the sheaves in said receptacle, and means cooperating with said sheaf delivery member for rendering the receptacle operable to dump the sheaves when an even number of sheaves in the receptacle has reached a predetermined height.

6. In a shocker, a frame, a sheaf receptacle pivotally carried thereby, a sheaf delivery member pivotally mounted on said frame for depositing the sheaves in said receptacle, operating mechanism for oscillating said sheaf delivery member, tripping mechanism operatively connected to said sheaf delivery member, and means for automatically rendering said tripping mechanism inoperative when an odd number of sheaves is in the receptacle.

7. In a shocker, a frame, a sheaf receptacle pivotally carried thereby, a tripping mechanism for controlling the actuation of said receptacle, a sheaf delivery member mounted on said frame, means for alternately deflecting the sheaf delivery member laterally from one side of said receptacle to the other side, and means controlled by the last named means for rendering the tripping mechanism inoperative.

8. In a shocker, a frame, a sheaf receptacle pivotally carried thereby, a sheaf delivery member mounted thereon having a tripping mechanism cooperating therewith, means for alternately deflecting the sheaf delivery member laterally from one side to the other side of said receptacle, and means controlled by the last named means for actuating said tripping mechanism when an even number of sheaves has been deposited in said receptacle.

9. In a shocking machine, a frame, a sheaf receptacle pivotally carried thereby a movable sheaf delivery member journaled thereon, a trip for actuating said receptacle carried by said frame and disposed at one side of the path of movement of said delivery member, a crank member journaled on said frame and capable of downward movement with respect to said frame, a clutch carried on said frame, operative connections between one end of said crank member and said trip and operative connections between the other end of said crank member and said clutch, and means disposed in the path of said crank for preventing the lateral movement of said crank. 55
10. In a shocking machine, a frame, a sheaf receptacle pivotally carried thereby, a movable sheaf delivery member journaled thereon, a tripping mechanism for controlling the actuation of said receptacle carried by said frame and disposed adjacent the path of movement of the delivery member, means for alternately deflecting the sheaf delivery member laterally from one side of the receptacle to the other, and means cooperating with the last named means for alternately rendering said tripping mechanism operative and inoperative. 60
11. In a shocking machine, a frame, a sheaf receptacle pivotally carried thereby, a movable sheaf delivery member journaled thereon, a tripping member for controlling the actuation of said receptacle carried by said frame and disposed offset with respect to the path of movement of said delivery member, means for alternately deflecting the sheaf delivery member laterally from one side of said receptacle to the other, and means cooperating with the last named means for alternately rendering said tripping member operative when said sheaf delivery member is delivering a sheaf on one side of said receptacle and inoperative when delivering a sheaf on the other side. 65
12. In a shocker, a frame, a sheaf receptacle carried thereby, an oscillating sheaf delivery member mounted on said frame having a tripping mechanism cooperating therewith, for controlling the actuation of said receptacle said delivery member being movable laterally from one side of the receptacle to the other side, and means controlled by the lateral movement of said de- 70
- livery member for alternately rendering said tripping mechanism operative and inoperative. 75
13. In a shocker, a frame, a sheaf receptacle pivotally carried thereby, a sheaf delivery member mounted on said frame, a tripping mechanism cooperating with said delivery member for controlling the actuation of said receptacle, means for alternately deflecting the sheaf delivery member laterally from one side to the other side of the receptacle, and means controlled by the last named means for actuating said tripping mechanism when an even number of sheaves has reached a predetermined height in said receptacle. 80
14. In a shocker, a frame, a sheaf receptacle carried thereby, an oscillating sheaf delivery member mounted on said frame, tripping mechanism cooperating with said delivery member for controlling the actuation of said receptacle, said member being movable laterally from one side of the receptacle to the other side, and means controlled by the lateral movement of said delivery member for alternately rendering said tripping mechanism operative when said delivery member is delivering a sheaf on one side of said receptacle and inoperative when delivering a sheaf on the other side. 85
15. In a shocker, a frame, a sheaf receptacle carried thereby, a sheaf delivery member mounted thereon, a tripping mechanism cooperating therewith for controlling the actuation of said receptacle comprising an outwardly movable shaft, and means for controlling the outward movement of said shaft for rendering said tripping mechanism inoperative. 90
16. In a shocker, a frame, a sheaf receptacle carried thereby, a sheaf delivery member mounted thereon, a tripping mechanism cooperating with the delivery member for controlling the actuation of the receptacle, means for laterally deflecting the delivery member, and means including a shaft controlled by said last mentioned means for permitting a downward movement of the shaft for alternately rendering the tripping mechanism operative and inoperative. 95
